MASARU KONDO, OF PUUNENE, MAUI, TERRITORY OF HAWAII

FUSE REFILLING TOOL

Application filed February 29, 1932. Serial No. 595,949.

The object of the invention is to provide a tool for use in connection with fuses where the fuse element is made replaceable, so that said element may be readily inserted and the 5 fuse thereby refilled; and to provide a tool of the kind indicated which is of simple form and therefore susceptible of cheap manufacture.

With this object in view, the invention consists in a construction and combination of parts of which a preferred embodiment is illustrated in the accompanying drawing but to which the invention is not to be restricted further than is imposed by any limitations 15 that may appear in the following claim.

In the drawing:

Figure 1 is a view partly in elevation and partly in section, showing the invention applied in operative position.

20 Figure 2 is an edge elevational view of the tool.

Figure 3 is a sectional view on the plane indicated by the line 3—3 of Figure 1.

Figure 4 is a perspective view of the bowed 25 spring member constituting an element of the jaws.

The invention is designed as a refilling tool for the placing of a fuse, such as indicated at 10, in a shell of the character of that indicated at 11. The tool comprises pivotally connected members of which each jaw member 12 is formed as an integral part of the handle member 14, the two handle members being normally forced away from each other 30 by an expansion spring 15. The handle members are provided with stop members 16 disposed on their inner sides and when the handles are forced toward each other against the pressure of the spring 15 until the stop 35 members 16 are in engagement, the jaw members 12 will be properly spaced.

The jaw members 12 at their extremities are provided with the lateral extensions 17 which constitute the real fuse holding elements in conjunction with similar extensions 40

18 formed at the extremities of the legs 19 of a bowed spring member which is secured to the two jaws 12 by rivets 20 or other fasteners. The legs 19 of the bowed spring thus lie flat against the jaw members 12 and 50 the extensions 18 on the legs of this spring member together with the lateral extensions on the jaws constitute cooperating elements between which the legs of the fuse 21 may be inserted so that the extremities may be 55 forced into the clips 22 and 23 of the shell.

The fusible part of the fuse 21 is the transverse portion 24, this being riveted or otherwise secured to the legs which are of relatively stiff metal.

60 The jaws of the tool are pivotally connected, so that their spacing may be varied to suit variations in the spacing in the clips 22 and 23 in various fuse shells, the jaws having the widest separation when the stop members 65 16 engage each other. The spacing may be reduced by inserting a filler between these stop members.

The handle portions of the tool are provided with insulating coverings to avoid liability of shock in the event the insertion of the fuse should be attempted without removal of the shell from the fuse block.

70 In the use of the invention, pressure on the handle members until the stops 16 engage 75 will result in the proper spacing of the jaws 12 and consequently in the proper spacing of the fuse holding elements, when a fuse of the kind indicated in the drawing may have its legs slipped between the lateral extensions 80 of the bowed spring member and of the jaws and the fuse then inserted. The tool may then be removed from engagement with the inserted fuse by lateral movement relative to the latter, after which releasing of the 85 hand will permit the spreading of the handles and movement of the jaws toward each other by the operation of the spring 15.

90 The invention having been described, what is claimed as new and useful is:

A tool of the kind indicated comprising pivotally connected members of which those portions on one side of the pivot constitute jaws and the remaining portions constitute handles, an expansion spring connecting the handles, stops carried by the handles and engaged with each other against the action of the spring, and a bowed spring member disposed between the jaws and secured to each, the legs of said member lying flat against the jaws and the latter and the spring member having lateral extensions constituting fuse leg engaging elements.

In testimony whereof I affix my signature.

MASARU KONDO.
